UNITED STATES PATENT OFFICE.

EDMOND A. WARREN, OF BROOKLYN, NEW YORK.

NUMBERING-MACHINE.

SPECIFICATION forming part of Letters Patent No. 320,103, dated June 16, 1885.

Application filed April 23, 1884. (No model.)

To all whom it may concern:

Be it known that I, EDMOND A. WARREN, of the city of Brooklyn, in the county of Kings, in the State of New York, have invented a new and useful Improvement in Numbering-Machines, of which the following is a specification, reference being had to the accompanying drawings.

In the various uses to which what are known as "numbering-machines," for printing consecutive numbers, can be put, it is sometimes desired to print numbers in regular succession once each, sometimes to repeat the printing of each of successive numbers several times, and sometimes to print alternate numbers.

One object of this invention is to provide for making the necessary changes in a numbering-machine to adapt it to the above-mentioned variations in the order of the numbers easily and quickly, and without requiring the removal of any parts of the machine and the substitution of other parts for them.

To the above end one part of my invention consists in a means of controlling the operation of the change-pawl, which acts on the ratchet-wheel of the numbering-head for turning the numbering-wheels, whereby the action of the said pawl and the consequent turning of the numbering-wheels may be suspended during a greater or less number of impression movements of the numbering-head, according to the number of times that the printing of each number is desired. Another part of the invention consists in means of varying the operation of the aforesaid pawl in such manner that it may be made to turn the ratchet-wheel of the numbering-head one or more teeth, according as it is desired to print the numbers in regular or in alternate order.

The invention also consists in novel means, hereinafter described, of operating and adjusting the operation of the inking apparatus in a numbering-press.

The invention further consists in a new kind of gage-holder, which provides for the easy and expeditious adjustment of the gage.

In the accompanying drawings, Figure 1 is a right-hand side view of the upper part of a numbering-machine with my improvement. Fig. 2 is a front view of the same. Fig. 3 is a side view of the repetition-wheel and its cam. Fig. 4 is a front view of the said wheel

and its stop-pawl. Fig. 4^a is a front view of the dog for operating the repetition-wheel, showing it in an inoperative position. Fig. 5^b is a side view of the upper part of the change-pawl. Fig. 4^c is a perspective view of the change-pawl on a larger scale. Fig. 5 is a left-hand side view corresponding with Figs. 1 and 2. Fig. 6 is a top view of the gage-holder. Fig. 7 is a front view of the same, partly in section, showing the clamp open. Fig. 8 is a view like Fig. 7, but showing the clamp closed. Fig. 9 is a transverse section of the gage-holder in the line x x. Fig. 10^d is a transverse section in the line y y. Fig. 11 is a front view of a modification of the gage-holder. Fig. 12 is a side view of some of the details of the inking apparatus.

Similar letters of reference indicate corresponding parts in the several figures.

A is the framing of the machine, provided with the usual guides, a a, for the upright slide B, to the lower end of which the numbering-head C is attached, and which is or may be operated in the usual manner through a lever, D, and rod E from a treadle. The numbering-head and its number-wheels b b' may be of the usual or any suitable kind and provided with the usual ratchet-wheel, c, through which the unit-wheel b' derives motion on its axis whenever desired, while the numbering-head makes an upward movement from the change-pawl d, pivoted to the framing at d'. The numbering-head also contains the bearings for and carries the main shaft F of the inking apparatus, which, as is common, is furnished at each end with a toothed sector, F', gearing with one of the fixed racks F'', secured to the framing, for the purpose of imparting to the said shaft the necessary oscillating motion as the numbering-head moves up and down.

G is what I call the "repetition-wheel" having ratchet-teeth on its periphery, and having in its face holes e e, corresponding with said teeth, and numbered, consecutively, 1 2 3 4, &c. This wheel is pivoted by a pin, f, to the lower guide, a, or other convenient part of the front of the framing, and it has attached to it at its back a cam, G', consisting of a plain circular and concentric ring having a notch, f'. (Shown plainly in Fig. 3 and dotted in Fig. 4.) The rear edge or cam-surface of this ring constitutes a bearing for a pin, d'', which is se-

cured in a prolongation of the change-pawl d , above its pivot d' , and it is only when the said pin d' is in or opposite the notch f' of the cam that the change-pawl d is capable of operating on the ratchet-wheel c , the said ring holding it out of gear at all other times. The said wheel G also has applied to its back a coiled spring, g , which always exerts a tendency to turn it in the direction of the arrow. 10 (Shown in Fig. 4.) When the notch f' of the cam is opposite the pin d' , the pawl-spring d^3 , applied to the change-pawl d , holds the said pin in the said notch, the square upper side of which bears against the said pin in such 15 manner that the latter serves as a stop by which the cam and the wheel G are prevented from being turned by the spring g , which then simply holds the wheel stationary. When the wheel is so held stationary, the machine 20 may be operated to print either consecutive or alternate numbers only once each, the pawl d being allowed to turn the ratchet-wheel c one tooth during every upstroke of the numbering-head, the slight movement required for 25 the pawl to slip over the teeth in the downward stroke of the head being permitted by the depth of the notch f' .

The repetition of the printing of a number is caused by suspending the operation of the 30 change-pawl d , and this suspension is what the cam G' , attached to the repetition-wheel, is intended to do, and in order to do it the said wheel is turned one tooth during each of as many strokes of the numbering-head as 35 there are repetitions to be made, the first down-stroke of the head turning the wheel far enough for the pin d' to be moved out of the notch f' by the action of the inclined side of the said notch, and successive strokes of the head causing 40 the turning of the wheel, so that the face of the cam-ring continues to hold the pawl out of gear until it is desired to stop the repetition and print another number, when the repetition-wheel is allowed to be turned back by 45 the spring g to the position for the pin d' to fall into the notch f' , and permit the pawl d to come into gear and turn the ratchet c during the next stroke of the numbering-head.

I will now describe the means of turning the 50 repetition-wheel to repeat the printing, and of regulating or determining the number of times it is turned, and the number of repetitions of the number produced.

The turning of the repetition-wheel for this 55 purpose is in the opposite direction to that produced by the spring g , and indicated by the arrow in Fig. 4, and is produced by the operation on the ratchet-teeth of said wheel of a dog, k , carried by the arm k^* of a short rock-shaft, k' , which works in a fixed bearing in a small bracket, k^2 , secured on the lower guide. This rock-shaft has an arm, k^4 , which is connected by a rod, k^5 , with an arm, k^6 , firmly attached to the slide B . The turning takes place 60 during each downward movement of the slide, and during the upward movement the repetition-dog k slips over the ratchet-teeth, being

permitted to do so by its pivoted connection k^{10} with the arm k^* and the spring k^7 , the latter holding the pawl against a stop-pin, k^9 , on the arm k^* , as shown in Fig. 2 in bold outline, which keeps the pawl rigid to the arm when moving in a direction to turn the wheel, but allows it to yield in going back. This connection of the dog also allows it to be turned back 70 to and held by the spring k^7 in the inoperative position illustrated in Fig. 4 when it is not desired to repeat the numbering, but is desired to leave the pawl d to operate at every stroke. The turning back of the repetition-wheel after every operation produced by the dog k is prevented by a stop-pawl, H , (shown best in Fig. 4,) which is pivoted to the frame by a fixed pivot, h , in a position to engage with the ratchet-teeth of the said wheel, as 80 shown in bold outline in Fig. 4. This stop-pawl has on its head a notched projection, h' , whose notch engages the end of a spring, h^2 , which is secured to the framing, and which will hold the said pawl either in gear with the 85 ratchet-teeth, as shown in bold outline in Fig. 4, or out of gear therefrom. Secured to the front of this pawl is a tongue, h^4 , which overlies the face of the repetition-wheel some 90 distance, as shown in Figs. 1, 2, and 5. 95

The determination of the number of repetitions of the numbering is effected by means of two pins, i and j , inserted in the holes e in the repetition-wheel G . The pin i , which I call the "zero-pin," is permanently fixed in the wheel in such a position that when the notch f' of the cam G' is opposite the pin d' of the change-pawl d the said pin i presses against the tongue h^4 in a direction to hold the stop-pawl H in gear with the ratchet-teeth. 100 The other pin, j , which I call the "variation-pin," is set in either of the holes 2 3 4, according to the number of impressions of each number required. Thus if two impressions are required, the said pin is placed in the hole 105 2, and if three are required it is placed in the hole 3, and so on.

The operation of repeating is as follows: The variation-pin j having been set in the proper hole e of the repetition-wheel, the machine starts with the zero-pin against the tongue h^4 , as just above described. The first downstroke of the numbering-head causes the dog k to turn the repetition-wheel one tooth, and so turn the cam G' far enough to throw the pin d' of the 110 change-pawl out of the notch f' , and so render the said pawl inoperative. At every down-stroke of the numbering-head this operation of the dog on the repetition-wheel is repeated, the said wheel being prevented by its stop-pawl H from returning until the variation-pin j strikes the tongue h^4 , which may be called the "unlocking-piece," and throws the stop-pawl H out of gear, and so allows the spring g to turn back the wheel and bring the cam-notch f' opposite to the pin d' of the change-pawl d and allow the said pawl to assume an 115 operative condition, so that in the next up-stroke of the numbering-head it will turn the 120 125 130 135

ratchet of the numbering-head and change the number. The operator of the machine (who cannot fail to have noticed the flying back of the repetition-wheel) now, before making another downstroke, takes hold of one of the pins *i* *j* and turns back the said wheel until the zero-pin *i*, coming under the tongue *h*', brings the pawl into gear again, and the next downstroke, before producing the impression, causes the dog *k* to turn the repetition-wheel and its cam far enough to throw the pin *d*² out of the cam-notch *f*', and throw the change-pawl out of gear, where it remains during successive strokes of the machine until the pin *j* again strikes the unlocking-piece *h*', and knocks the pawl *H* out of gear and permits the return of the wheel and cam to the position to permit again the operation of the change-pawl.

20 The repetition-wheel may have a large number of holes and teeth, and so provide for numerous repetitions of consecutive or alternate numbers. If a greater number of repetitions is required than is provided for by the said wheel, the dog *k* may be turned out of gear, as shown in Fig. 4^a, and the wheel locked by the pawl in a position to hold the change-pawl *d* out of gear.

In order to provide for turning the change-wheel *c* either one tooth at a time to print consecutive numbers or two teeth at a time to print alternate numbers, as is often required, the pin *d*², in the upper part of the change-pawl *d*, is made adjustable forward and backward in a slot, *d*³, (shown in Fig. 4^b,) provided for it in the pawl, and capable of being secured in either the forward position shown in Figs. 1 and 4^c or in the backward position shown in Fig. 4^b by a thumb-nut, *d*⁵, applied to a screw-thread on the said pin, the said screw thread and nut serving to clamp the collar *d*⁶, Fig. 4^c, on the said pin against the inner face of the upper part of the pawl. When the said pin is in the forward position, (shown in Figs. 1 and 4^c,) its bearing against the cam *G* will only permit the point of the pawl to approach near enough to the vertical plane passing through the axis of the change-wheel *c* as to enable it to turn the said wheel one tooth at a time; but when the said pin is in the backward position (shown in Fig. 4^b) the point of the pawl may approach nearer to said line, and so be permitted to engage with the ratchet-wheel earlier in the stroke and remain in engagement with one tooth long enough to turn it a distance equivalent to two teeth. This adjustment of the pawl may be used either in repeating or for printing the numbers consecutively or alternately without repeating.

6c I is the inking-table, placed behind the numbering-head, with its face presented in a forward direction and inclined, as shown in Fig. 1. It is arranged on a shaft or axle supported in a stationary arm, *A'*, secured to the framing *A*, and it has no other than a simple rotary motion, its axis being fixed. Its rotary motion is produced by the action upon a

ratchet-wheel, *I*², firmly secured to it, of a pawl, *I'*, which may derive motion by a connection with the lever *D* or from some other suitable moving part of the machine.

J is the inking-roller, the shaft *J'* of which is carried in the lower ends of two levers, *K* *K*, which work on fulcrum-pins *ll*, secured in the two arms *F' F'*, fast to the rock-shaft *F*. 75 The upper ends of the said levers *K* *K* are connected by springs *m* with the upper parts of the said arms *F' F'*. The movement of the roller over the table is produced by the oscillation of the rock-shaft *F*, which is produced 80 by the sectors *F'*, hereinbefore described, running in the fixed racks *F*² as the numbering-head moves up and down, and the levers *K* *K*, in which the roller is carried, being allowed an independent movement, the roller is 85 permitted to be brought by the springs *m* with a nearly equal pressure over all parts of the surface of the table without requiring the table to have any oscillating movement. The table having only a rotary motion and being 90 held firmly at a fixed inclination, the inking-roller can pass all the way from top to bottom of its face, and therefore the whole of the surface of the table can be utilized. Moreover, the ink-surface of the table being in front, its 95 condition may at all times be seen by the operator.

For the purpose of adjusting the inking-roller to the printing surfaces of the numbering-wheels, set-screws *n* *n* (shown best in Fig. 100 12) are screwed through lugs *n' n'*, provided on the arms *F' F'*, and made to press upon the levers *K* *K* in a manner to bring the roller nearer to or farther from the shaft *F*, which is directly over the axis of the numbering-wheels, and thereby to make the roller come 105 more or less close to or press harder or not so hard on the printing-surfaces.

P is the bar, at the extremity of which is formed the gage-holder, the said bar being 110 adjustably attached in the usual or any suitable manner to the frame of the machine. In Figs. 2, 5, 6, 7, 8, 9, 10 the front end of this bar is formed into a clamp to receive the piece of card or stiff paper *v*, commonly used as the 115 gage, the fixed jaw *p* of the clamp being formed by reducing the upper side of the bar *P* to a flat surface, and movable jaw *p'* being composed of a thin and flexible steel blade attached to the bar *P* at the end farthest from 120 the end of the said bar by a screw or rivet, *p*². The end of the bar *P*, which is left round, is fitted with a thimble or collar, *Q*, which turns freely upon it, and this thimble has in it a notch, *q*, of a size and form to allow the end 125 of the blade *p'* to pass in and out, as will be understood by reference to Fig. 6. Near the head or outer end of this collar or thimble there is a slot, *q'*, to receive a pin, *q*², which is 130 screwed into the bar *P*, and which keeps the thimble from slipping off, but permits it to turn sufficiently to insert the piece of card or paper into the clamp. The thimble is turned to the position shown in Figs. 6, 7, and 9, in which

the end of the blade or movable jaw p' is free to enter the notch q and spring slightly outward. On the paper or card having been inserted the thimble is turned, and the notch, 5 passing the blade, the closed portion of the thimble covers and presses on the end of the blade or movable jaw, as shown in Fig. 8, and produces the clamping of the paper, which is permitted to be removed or readjusted by simply turning back the thimble to the position first mentioned.

The clamp form of the gage-holder affords very much greater convenience for the attachment, adjustment, and changing of the gage 15 than is afforded by the common method of fastening a piece of cloth to the holder and pasting the card or paper gage to this cloth.

In the modification shown in Fig. 11 there is attached to the bar P a clamp composed of 20 a fixed jaw, R , and a movable jaw, S , hinged thereto at t , and a clamping-screw is applied at u .

What I claim as my invention, and desire to secure by Letters Patent, is—

25 1. The combination, with the numbering-head and the change-pawl for effecting the changes of numbers therein, of a cam for throwing and holding the said pawl out of gear, a ratchet-wheel connected with said cam, a dog carried by the numbering-head for operating 30 said ratchet-wheel and cam to produce the throwing and holding of the change-pawl out of gear, a stop-pawl for stopping said ratchet-wheel, a pin carried by said cam and wheel 35 for unlocking the stop-pawl, and a spring for returning the cam to the position for letting the change-pawl come into gear, substantially as herein described.

2. The combination, with the numbering-head, of the change-pawl carrying a pin at its 40 upper end, a cam turning about a fixed axis and having a notch for the reception of said pin, a ratchet-wheel attached to said cam, and having holes in its face fitted with an adjustable pin, and actuated by the movements of the 45 numbering-head, a spring for moving the cam

in the opposite direction to that in which it is turned by the movement of the numbering-head, a stop-pawl for holding the said ratchet-wheel, and an unlocking-piece carried by said stop-pawl to be operated by said adjustable pin for throwing the stop-pawl out of gear, all substantially as herein described. 50

3. The combination of the change-pawl d , the notched cam G' for operating on said pawl, the spring g , applied to the said cam, the ratchet-toothed repetition-wheel G , attached to said cam and perforated for the reception in variable positions of a movable pin, the fixed and movable pins i and j , carried by said wheel, 60 the stop-pawl H , for stopping said wheel, and the unlocking-piece h' , attached to said pawl and operated by the said fixed and movable pins for throwing the said pawl into and out of gear, all substantially as herein described. 65

4. The combination, with the change-pawl and ratchet-wheel of a numbering head, of a pin adjustable in the said pawl and a bearing for the said pin, whereby the pawl is made to turn the said wheel one tooth or two teeth at 70 a time, substantially as herein described.

5. The combination, with the reciprocating numbering-head and the stationary racks F' F'' , of the rock-shaft F , carried by said numbering-head and furnished with sectors F' F'' 75 and arms $F' F''$, the inking-roller levers $K K$, carried by said arms, and the adjusting-screws $n n$ in said arms, for adjusting the said levers and the inking-roller, substantially as herein described. 80

6. The combination, with the gage-carrying bar, of a gage-holder consisting of a clamp, substantially as herein described.

7. The gage-clamp composed of the fixed jaw p , the elastic movable jaw p' , and the 85 notched thimble or collar attached to and turning on the fixed jaw, substantially as herein described.

EDMOND A. WARREN.
